H. L. HOARD

MASSAGE DEVICE

Filed March 22, 1919

Inventor
Halbert L. Hoard,
Erwin, Wheeler & Woolard,
Attorneys.

UNITED STATES PATENT OFFICE.

HALBERT L. HOARD, OF FORT ATKINSON, WISCONSIN.

MASSAGE DEVICE.

Application filed March 22, 1919. Serial No. 284,427.

To all whom it may concern:

Be it known that I, HALBERT L. HOARD, a citizen of the United States, and residing at Fort Atkinson, in the county of Jefferson 5 and State of Wisconsin, have invented a certain new and useful Improvement in Massage Devices; and do hereby declare that the following is a full, clear, and exact description thereof, such as will enable persons skilled in the art to which the invention pertains to make and use the same, reference being had to the drawings hereto attached for disclosure as to details of construction.

My invention relates to a machine for massaging the special feeding tissues that join the spinal cartilages and ligaments, so as to stimulate especially the restoration of the intervertebral disks when in an emaciated or diseased condition, thus removing 20 pressure from the spinal nerves.

My invention further relates to a machine of the type referred to, and which may be operated by the person desiring treatment, so that the services of an attendant heretofore required in connection with the use of 25 similar machines, are dispensed with.

The machine, in the general form of a table, is provided with a flexible covering which is held taut so as to support the body 30 of the person, when reclining thereon, and devices for taking up the slack in the flexible covering are provided, so that the body of the recumbent person may rest at the proper level to enable the massage rollers, which are 35 arranged to travel at the underside of the covering to perform their functions in a proper manner.

A reciprocating carriage is arranged in the frame-work and is adapted for longitudinal 40 movement under the flexible covering upon which rests the patient to be treated. The carriage is equipped with massage rollers which are spaced so as to bear upon the back of the patient, in lines parallel with and at 45 each side of the spine. The carriage with the massage rollers is moved by means of connections to a handle or bar, within easy reach of the patient when in position, on the table, so that treatment may be readily administered.

In the accompanying drawings,

Figure 1 is a side elevation of my massaging machine.

Figure 2 is a plan view thereof, broken out

through the flexible covering to show the 55 carriage for the massage rollers.

Figure 3 is a vertical section on the line 3-3 of Figure 1, looking in the direction of the arrow.

In the drawing, the frame or table A, is 60 composed of legs a, side rails a', end rails a'', and end cross bars a'''.

The table is open at the top, and is covered with a suitable flexible fabric B, which for convenience in construction is formed in sections. The head section b and the foot section b' are stretched over the table, and secured in place by attachment to the rails at 65 b'', in such manner that the said sections are maintained substantially level at all times. 70

The central section C of the covering is attached at one edge to one of the side rails a', and at the other edge to a rod c, about which it may be wound so as to take up any slack, or to adjust the plane thereof at the proper 75 height with reference to the path traveled by the massage rollers, hereinafter described.

The winding rod c is journaled in bearings c', c' on the side rail, and extends to the head of the frame, where it is passed through a 80 guide c'' attached to the end rail. The outer end of the rod is formed as a crank c'', by means of which the rod may be rotated for the purposes mentioned. At a point near the crank, the rod c is provided with a ratchet 85 c', with which co-operates a pawl c'' connected to the frame. The said pawl, by its engagement with the teeth of the ratchet, will serve to hold the winding rod in whatever position of adjustment may be desired for 90 the accomplishment of its purposes in holding the central section C of the covering at the desired height.

The spinal portion of the body of the person to be treated will rest upon the central 95 section of the flexible covering, and I therefore have provided the means described for adjusting the plane of the said section to accord with the sensitiveness of the person using the apparatus. A pillow D will be 100 placed at the head of the apparatus for the comfort of the user.

A bar E, extends longitudinally of the frame between the end cross bars a''', to which it is detachably connected by means 105 of screws, as shown. The upper edge of this bar is beveled at each corner as indicated at e, and the lower edge is rounded at e'.

2
A carriage F is mounted to have longitudinal movement on the bar E. This carriage is composed of two side plates e^{10} separated by spacers e^{11} , and between the 5 plates are grooved supporting and guiding rollers e^2 , e^2 , which travel on the beveled edge e of the bar F. A yoke piece e^3 is attached to the carriage by means of cap screws e^4 , which pass through one branch 10 of the yoke, and into one of the side plates e^{10} . Brackets e^5 , e^5 are placed at the inner side of the branches of the yoke, so as to form forks, in which are journaled the 15 massage rollers G. An end of one of the brackets e^5 is extended below and curved at e^6 so as to pass under the rounded edge e' of the bar E, so as to hold the carriage to its path of travel on the said bar. The 20 cap screws e^4 pass through the left hand branch of the yoke and the longer bracket e^5 and secure the parts to the corresponding side plate e^{10} . The bend of the yoke is 25 resilient and tends to separate the branches thereof, but a cap screw e^7 is employed to restrain the resiliency and hold the massage rollers when adjusted in the desired relation to each other.

Brackets H, depending from the side rails a' , support the journaled ends h of a bail 30 or handle bar h' , the central horizontal portion h^2 of which extends over the apparatus, and within reach of the patient, so that he may easily grasp the same and thus move the massage rollers to 35 effect the desired treatment. A curved link h^3 is journaled at its mid-length in the carriage F, and is also journaled at its ends in collars h^4 , adjustable on the parallel side arms of the bail or handle bar, so as to

regulate the extent of movement of the carriage, under a movement of the said handle bar through a given distance. 40

In use, the patient reclines upon his back, and is supported in part by the flexible covering section C, and the massage rollers 45 G, the patient taking a position with one roller at each side of his spinal column. If the handle bar is then reciprocated, the rollers will move with a kneading pressure along the spinal portion of the body. If 50 the body is sensitive, the roller pressure will, of course, be relieved by increasing the tension of the apron section C, to carry an increased portion of the load.

By means of my improved apparatus, but 55 very little manual effort upon the part of the patient to apply a very thorough massaging movement to the muscles and parts which it is desired to treat will be required. 60

Having thus described my invention, what I desire to secure by Letters Patent, is:—

In a massage apparatus, a frame, a flexible support for the body of the patient while recumbent, a carriage longitudinally 65 reciprocable in the frame, massage rollers mounted upon said carriage, and connections to the carriage whereby the latter may be operated to apply massage treatment to the body of the patient. 70

In testimony whereof, I have signed my name at Fort Atkinson, Wisconsin, this 19th day of March, 1919.

HALBERT L. HOARD.
